[57] CLAIM

The ornamental design for rural mailbox signaling device, as shown and described.

DESCRIPTION

FIG. 1 is a perspective view of the signaling device of the present invention;

FIG. 2 is a front elevational view of the signaling device of FIG. 1;

FIG. 3 is a rear elevational view of the signaling device of FIG. 1;

FIG. 4 is a right side elevational view of the signaling device of FIG. 1;

FIG. 5 is a left side elevational view of the signaling device of FIG. 1;

FIG. 6 is a top plan view of the signaling device of FIG. 1;

FIG. 7 is a bottom plan view of the signaling device of FIG. 1;

FIG. 8 is a front elevational view of another embodiment of the signaling device of the present invention containing a representation of the United States flag with shading indicating color; and,

FIG. 9 is a rear elevational view of the signaling device of FIG. 8.

The other views of the second embodiment will appear the same as FIGS. 4-7 except that the views corresponding to FIGS. 4 and 5 will show the flag.

FIG. 1

FIG. 2

FIG. 3

FIG. 4

FIG. 5

FIG. 6

FIG. 7

FIG. 8

FIG. 9
